2,047,879

COMBINED AMPLIFYING AND RECTIFYING SYSTEM

Michel Mackoud, St. Albans, N. Y., assignor to
The Electron Corporation, East Orange, N. J.,
a corporation of New Jersey

Application July 1, 1933, Serial No. 678,660

20 Claims.

(Cl. 250—27)

This invention relates to apparatus for amplifying and rectifying alternating, oscillating, and variable currents independently and in combination, and is particularly adapted for use in conjunction with radiant energy systems and for adapting such systems to operate from power supply circuits generally used for house lighting purposes which may supply either direct, pulsating, or alternating currents.

10 The invention involves the provision of amplifying and rectifying apparatus either independent of each other or combined for employing and operating a translating device operating as a rectifier, an amplifier, or an oscillator, and the like.

15 The invention further comprehends the provision of circuit means for operation in conjunction with properly constructed electron discharge devices to amplify and rectify varying currents of different frequencies, such as are common to the transmission of intelligence by radiant energy, the reception and reproduction thereof, or the rectification of varying or oscillating currents used for power purposes in order to convert such currents for use in any desired manner, together with means for controlling the potential and other characteristics of the transformed current and, when desired, applying them to the electrodes of the electron discharge devices.

20 These and many other objects as will appear from the following detailed disclosure are secured by means of this invention.

25 This invention resides substantially in the combination, construction, arrangement, relative location of parts, and circuit connections, all as will be described below.

30 This application is a continuation in part of my copending application Serial No. 120,376, filed July 3, 1926, Patent No. 1,920,576, August 1, 1933.

35 Referring to the drawing—

Figure 1 is a diagrammatic illustration of the association of apparatus in accordance with this invention as applied for purposes of illustration to a cascade rectifying and amplifying system; and

40 Figure 2 is a diagrammatic illustration of the association of apparatus in accordance with this invention as applied to amplifying devices connected in parallel to provide the so-called push-pull amplifier.

45 As shown in Fig. 1, the input circuit is illustrated by way of example, as a tuned, grounded antenna system having the primary 1 of a coupling transformer inductively coupled to its secondary 2. One terminal of the secondary is con-

nected to the grid 7 of the electron discharge device and its other terminal is connected by wire 11 to the cathode circuit through wire 18, a portion of the potentiometer 15 and wire 14. This input circuit is provided with a variable condenser 3 by means of which it may be tuned to desired frequencies. The electron discharge 4 is provided with a cathode sleeve 8 of the equi-potential type which is provided, in accordance with the usual practice, with a suitable electron 10 emissive coating. Disposed within the cathode sleeve is the heater element 9 which is shown as divided into two portions oppositely wound to provide a non-inductive heater. Numerous other methods of winding filaments non-inductively 15 may be employed to minimize or eliminate the electro-magnetic and electro-static fields that may be formed.

At 10 is the plate anode connected in the output circuit as will be described. In a similar way 20 there is provided the electron discharge devices 5 and 6, each of which has a grid 7, cathode sleeve 8, heater 9, and anode 10. All of the heaters 9 are illustrated as non-inductively wound and are made of a suitable resistance wire in accordance 25 with well known principles, which may be either electronically emissive by reason of the nature thereof, or may be coated in accordance with well known practice with a suitable emitting coating. The heaters 9 are proportioned and designed 30 for direct connection to a 110-volt direct or alternating current lighting circuit by means of the wires 19 and 20, 21 and 22, and 23 and 24. As shown, these heaters are connected in parallel but may, upon proper design, be connected 35 in series for direct operation from a 110-volt or alternating current lighting circuit.

Connected across the leads 19 and 20 is a potentiometer 25 shunted by a by-pass condenser as shown. An adjustable tap is connected by 40 wire 26 through the choke coils 27 and 28 to the output circuits of the vacuum tubes. Thus the plate anode 10 of the tube 6 is connected to wire 26 through the sound reproducing device 29 shunted by the by-pass condenser 31 and the wire 45 32. The output electrode 10 of tube 4 is connected through the primary 35 of a coupling transformer and by wires 36 and 38 to wire 26. Likewise plate anode 10 of tube 5 is connected through the feed-back winding 42, primary 37, 50 and a coupling transformer, and wire 38 to wire 26.

55 The secondary 40 inductively coupled with the primary 35 is connected at one terminal through the usual grid leak system 41 to the grid 7 of the

tube 5. The other terminal of the winding 48 is connected by wire 12 to the wire 11. The feedback coil 42 is inductively coupled with the winding 48 and is shunted by a tuning condenser 43 in accordance with the known practice. The primary 37 and secondary 44 are interconnected by means of a variable condenser 45 for the purpose of providing a grid bias for the grid 7 of tube 5. The connection of this grid to the output circuit of the preceding tube through the variable condenser 45 provides a convenient and suitable grid biasing arrangement. The value of the bias will of course, depend upon the values of the grid leak system 41, which may be adjustable in value if desired. The primary 37 is shunted by a bypass condenser 39 and is inductively coupled with the secondary 44, one terminal of which is connected to grid 7 of tube 5. The other terminal of secondary 44 is connected by wire 13 to wire 11.

It will be noted that all of the grids 7 are connected through the common wire 11, wire 18, and potentiometer 15 to their respective cathode sleeves 8. The transformer comprising the windings 37 and 44 is shown as an iron core transformer in accordance with the usual practice since the tube 5 is a rectifying tube and the tube 6 is an audio amplifier. Windings 37 and 44 are interconnected by a variable condenser 45 to provide, as before, a suitable grid bias for the grid of tube 6 from the plate circuit of tube 5. However grids 7 are biased with respect to their cathodes by having their respective returns made to the resistance 15 by means of connection 18 which is at a lower resistance than any potential at 8, by means of the potential voltage drop of 15.

The condensers 33, in conjunction with the choke coils 27 and 28, provide a filter for a purpose to be described. These condensers are connected by wire 34 to wires 11 and 18.

With this arrangement alternating currents, such as represented by a radio signal, are amplified at radio frequency, rectified, and amplified at audio frequency. As illustrated, two of these tubes likewise provide for themselves the necessary operating potentials and for the third tube as well. Thus the tubes 4 and 5 are so connected as to provide a full wave rectifier energized from the heater circuit, the rectified current being applied to the plates thereof and to the plate of the tube 6. In addition provision is made for the necessary bias on the various electrodes. Thus each of the tubes 4 and 5 comprise half wave rectifiers of alternating currents, the outputs of which are combined in a suitable filter system to provide full wave rectification and hence necessary direct current potentials for the anodes. The heaters 9, in conjunction with the sleeves 8 of the tubes 4 and 5, provide half wave rectifiers in which the heaters 9 are the cathodes and the sleeves 8 are the anodes. The sleeves 8 are at positive potential with respect to the heaters through the connection 14, potentiometer 15, wires 18 and 34, wire 26 and back through potentiometer 25 to the circuit 19-20.

The wires 34 and 26 provide the output circuit for the full wave rectifier provided by these tubes, in which circuit is included the filter system comprising the condensers 33 and the choke coils 27 and 28. This system is provided for the purpose of smoothing out any ripples and variations in the rectified current. The rectified current is then impressed upon the anodes 10 through the wire 26 to render them positive and the return circuit for these anodes to the cathodes 8 is pro-

vided through the wires 34, 18, potentiometer 15, and wires 14, 16 and 17.

In all of the tubes 4, 5, and 6 in carrying on their usual amplifying and rectifying operations for the radio signal, the sleeve 8 is the cathode thereof to supply electrons for the anodes 10 which are controlled by the grids 7. It will be noted that the tubes 4 and 5 as connected not only provide the necessary direct current potentials for the plates, but likewise provide the direct current potential for the plate of tube 6 which is not part of the rectifying system.

As described above, the grid bias potentials for tubes 5 and 6 are provided from the plate circuits of the preceding tubes through the agency 15 of the connection through the condensers 45. However, the grid bias potentials may be derived from connection 18 which is at lower potential than any of the cathodes 8 in the circuit, by means of the resistance voltage drop in 15. 20

Grid 7 of tube 4 is given the necessary negative bias with respect to its cathode 8 through the potentiometer 15. The anodes 10 are likewise derived through necessary potentials directly from the relatively high voltage filament circuits 25 which are energized from 110 or even, if properly designed, 220-volt direct or alternating current lighting circuit. This plate voltage is provided by the voltage drop through the filament circuits which would be of the order of 20 volts, thus providing a potential for the plates of the order of 90 volts when the heaters are energized by 110 volts. 30

The principles of this invention have been shown applied to a push-pull amplifier which, in addition, is connected to rectify and provide its own plate potentials and, in addition, the necessary potentials for any additional associated equipment employing electron discharge devices and the like. The input is impressed upon the primary 50 of an amplifying transformer having 40 a secondary 51. The terminals of this secondary are connected to the grids 53 and 55 of the electron discharge devices 52 and 54, respectively. These devices include equi-potential cathode sleeves 56 and 57 which are coated with a suitable 45 electron emitting coating. Each sleeve is heated by an indirectly reversely wound non-inductive heater 61 and 62, respectively. These heaters are respectively connected across the secondaries 63 and 64 of a transformer and are proportioned to 50 supply any suitable voltage thereto.

At 65 is a third secondary which, together with the secondaries 63 and 64 are inductively coupled with the primary circuit 66 to be energized from a power supply circuit as described before. The sleeves 56 and 57 are connected together by a wire 68 and then by a common wire 69 through a suitable grid leak system 60 to an adjustable tap connection of secondary 51. The ends of the secondary 65 are connected by adjustable midpoint taps to the secondaries 63 and 64. The plate anodes 67 and 68 are connected to the terminals of the primary 66 and the output transformer, the secondary 70 of which is connected to any device to be energized therefrom. An adjustable midpoint tap connection of secondary 65 is connected by wire 71 through a choke coil 72 to a midpoint adjustable tap connection on primary 69. Both sleeves 56 and 57 are connected by wire 73 to a wire marked C-. Wires 70 71 and 73 are bridged by condensers 74 which, in connection with the choke coil 72, provide a suitable filter circuit. Wires 71 and 73 are also shunted by a suitable resistance 75 to provide a potentiometer having adjustable tap connec- 75

tions marked B- and B+. The wire B+ is connected to the wire 11. With this arrangement it will be again apparent that the tubes 52 and 54 are connected together to provide the usual push-pull amplifier for amplifying signal energy and are also connected together to provide a full wave rectifier which applies the operating potentials for themselves. In addition, there is provided, through the wires C-, B-, B+ and B+ the necessary connections for providing the potentials for any other devices to be operated in conjunction with the amplifier, such as additional electron discharge devices associated in the circuits thereof in accordance with many well known circuit practices.

The principle of employing the combined amplifying and rectifying tubes for supplying operating potentials to other equipment as well as their own operating potentials is not confined to the circuit of Figure 2. The circuit combination of Figure 1 is capable of and actually operates for the same purpose. In the circuit of Figure 1, all three of the tubes illustrated have both amplifying and rectifying functions. However, the circuit is equally operable and within the scope of this invention if some of the tubes have amplifying functions only. The circuit connections, as illustrated in Figure 1, are such that if only one or two of the tubes have rectifying functions in addition to their amplifying functions the operating potentials will be supplied not only for themselves but for the other tubes of the circuit. Indeed, in practice this condition will invariably arise. Since the heaters 9 are sources of electrons which flow to the anodes 8 of the rectifiers, it will be apparent that as the heaters age they will lose their electron emitting properties to different degrees and might in some cases for all useful effects entirely lose their electron emitting properties without losing their function of heating the sleeves 8 to supply electrons for the anode 10. In this case, it is apparent that the necessary operating potentials for those tubes whose rectifying properties have become impaired will be supplied from the rectifiers of the other tubes by reason of the circuit connections employed.

From the above description it will be apparent that I have provided a new and novel invention which may be embodied in many physical forms and in many circuit associations without departure from the principles and scope thereof. I do not, therefore, desire to be strictly limited to the disclosure as given for purposes of illustration but rather to the scope of the appended claims.

What I seek to secure by United States Letters Patent is:

1. The combination as described comprising three audions each having a grid, a cathode emitter and a plate, means for coupling said audions together to provide a cascaded radio frequency amplifier, detector and audio frequency amplifier, heaters for said cathode emitters, a circuit for energizing said heaters, a resistance connected between two of said cathode emitters, a resistance connected across the circuit for energizing the heaters, and connections from said resistances to the grids and anodes of said audions to provide operating potentials.

2. The combination as described comprising three audions each having a grid, a cathode emitter and a plate, means for coupling said audions together to provide a cascaded radio frequency amplifier, detector and audio frequency amplifier,

heaters for said cathode emitters, a circuit for energizing said heaters, a resistance connected between two of said cathode emitters, a resistance connected across the circuit for energizing the heaters, connections from said resistances to the grids and anodes of said audions to provide operating potentials, and a filter circuit in said connections.

3. In an amplifying and full wave rectifying system the combination comprising a pair of audions each having a grid, a cathode emitter and a plate, an input circuit connected to said grids, an output circuit connected to said plates, a connection between said cathode emitters and said input circuit, heaters for said cathode emitters, means for energizing said heaters, a connection from said means to the output circuit, a connection from the cathode emitters, and a potentiometer having a plurality of variable taps connected between said connection and the connection between said means and the output circuit.

4. In an amplifying and full wave rectifying system the combination comprising a pair of audions each having a grid, a cathode emitter and an anode, means for connecting said audions to provide an amplifier, heaters for said cathode emitters, means for energizing said heaters, circuit connections between said cathode emitters and said means for providing operating potentials for said audions, a filter circuit in said connections, and a potentiometer in said connections having a plurality of variable taps for providing additional operating potentials.

5. In an apparatus as described the combination comprising two audions each having a grid, a cathode emitter and a plate, input circuits connected to said grids, output circuits connected to said plates, heaters for said cathode emitters, circuits for energizing said heaters, an impedance connected between said emitters, an impedance connected across said energizing circuit, and connections between said impedances said said grids and plates to provide operating potentials therefor.

6. An amplifying circuit as described including a pair of audions each having cathode, grid and anode elements, an input circuit and an output circuit for each audion including the grid and anode electrodes respectively, heaters for said cathodes, a resistance connected across said heaters having a variable connection, means for energizing said heaters with direct or alternating current, the anode operating potentials being provided by the voltage drop in the electron stream between said variable connection and the cathodes.

7. In a circuit as described an audion having a grid, a plate and a cathode, input and output circuits connected to said grid and plate respectively, a heater for said cathode, a resistance shunted across the heater having a variable tap, a circuit for energizing said heater with either direct or alternating current, and connections from said plate circuit and heater circuit for supplying operating potentials for said anode equal to the potential applied to said heater minus the voltage drop in the electron stream between said tap and the cathode.

8. In an amplifying system, the combination comprising two audions each having a grid, a plate, and a cathode, a heater for each cathode, an input circuit for each audion including its grid, an output circuit for each audion including

its plate, the output circuit of one audion being coupled to the input circuit of the other audion, a resistance connected between said cathodes, and connections between said resistance and the input circuits.

9. In a combined rectifying and amplifying system, the combination comprising two audions each having a grid, a cathode, a plate, and a heater, a circuit for energizing said heaters from either direct or alternating current, an impedance connected between said cathodes, an impedance connected in said heater circuit, a filter connected between said impedances, an input circuit for each audion including its grid, an output circuit for each audion including its plate, the output circuit of one audion being coupled to the input circuit of the other audion, and connections from the output circuits to the filter whereby operating potentials for the plates are supplied.

10. In a circuit as described the combination including an audion having cathode means, a grid and an anode, an input circuit connected between said cathode means and grid, an output circuit connected between said cathode means and anode, a heater adapted to be energized by electric current for activating said cathode means, means including connections between the heater and the cathode means for supplying operating potentials for the input and output circuits, a second audion having input and output circuits, and connections from said means for supplying operating potentials for its input and output circuits.

11. In a circuit as described the combination including an audion having cathode means, a grid and an anode, an input circuit connected between said cathode means and grid, an output circuit connected between said cathode means and anode, a heater adapted to be energized by electric current for activating said cathode means, means including connections between the heater and the cathode means for supplying operating potentials for the input and output circuits, a second audion having cathode means and grid and anode electrodes, input and output circuits including said grid and anode respectively, said second audion being operatively associated with the first mentioned audion, and connections from said means for supplying grid and anode operating potentials for the second audion.

12. In an amplifying and full wave rectifying system the combination comprising two audions each having a grid, a plate and a cathode emitter, a heater for each emitter, an input circuit for each audion including its grid and emitter, an output circuit for each audion including its plate and emitter, connections to said heaters for energizing them with alternating current, means including connections between the heaters and cathode emitters of said audions to provide full wave rectification for alternating current operation and connections between said plates and said means to impress operating potentials on said plates.

13. In an amplifying and full wave rectifying system the combination comprising two audions each having a grid, a plate and a cathode emitter, a heater for each emitter, an input circuit for each audion including its grid and emitter, an output circuit for each audion including its plate and emitter, means for coupling the output circuit of one audion to the input circuit of the other audion, connections to said heaters for energizing them with direct or alter-

nating current, means including connections between the heaters and cathode emitters of said audions to provide full wave rectification for alternating current operation and connections between said plates and said means to impress operating potentials on said plates.

14. In an amplifying and full wave rectifying system the combination comprising two audions each having a grid, a plate and a cathode emitter, a heater for each emitter, an input circuit for each audion including its grid and emitter, an output circuit for each audion including its plate and emitter, connections to said heaters for energizing them with direct or alternating current, means to provide full wave rectification for alternating current operation and continuous conductivity for direct current operation including connections between the heaters and cathode emitters of said audions, and connections from said means to said plates to impress operating potentials on said plates for either direct or alternating current operation.

15. In an amplifying and full wave rectifying system the combination comprising two audions each having a grid, a plate and a cathode emitter, a heater for each emitter, an input circuit for each audion including its grid and emitter, an output circuit for each audion including its plate and emitter, means for coupling said audions to form a cascade amplifier, connections to said heaters for energizing them with direct or alternating current, means to provide full wave rectification for alternating current operation and continuous conductivity for direct current operation including connections between the heaters and cathode emitters of said audions, and connections from said means to said plates to impress operating potentials on said plates for either direct or alternating current operation.

16. In an amplifying and full wave rectifying system the combination comprising two audions each having a grid, a plate and a cathode emitter, a heater for each emitter, an input circuit for each audion including its grid and emitter, an output circuit for each audion including its plate and emitter, connections to said heaters for energizing them with direct or alternating current, means including connections between the heaters and cathode emitters of said audions to provide full wave rectification for alternating current operation, and connections between said grids and said means to impress operating potentials on said grids.

17. In an amplifying and full wave rectifying system the combination comprising two audions each having a grid, a plate and a cathode emitter, a heater for each emitter, an input circuit for each audion including its grid and emitter, an output circuit for each audion including its plate and emitter, means for coupling the output circuit of one audion to the input circuit of the other audion, connections to said heaters for energizing them with direct or alternating current, means including connections between the heaters and cathode emitters of said audions to provide full wave rectification for alternating current operation, and connections between said grids and said means to impress operating potentials on said grids.

18. In an amplifying and full wave rectifying system the combination comprising two audions each having a grid, a plate and a cathode emitter, a heater for each emitter, an input circuit for each audion including its grid and emitter, an output circuit for each audion including its plate

and emitter, connections to said heaters for energizing them with direct or alternating current, means to provide full wave rectification for alternating current operation and continuous conductivity for direct current operation including connections between the heaters and cathode emitters of said audions, and connections from said means to said grids to impress operating potentials on said grids for either direct or alternating current operation.

19. In an amplifying and full wave rectifying system the combination comprising two audions each having a grid, a plate and a cathode emitter, a heater for each emitter, an input circuit for each audion including its grid and emitter, an output circuit for each audion including its plate and emitter, means for coupling said audions to form a cascade amplifier, connections to said heaters for energizing them with direct or alternating current, means to provide full wave rectification for alternating current operation and continuous conductivity for direct current

operation including connections between the heaters and cathode emitters of said audions, and connections from said means to said grids to impress operating potentials on said grids for either direct or alternating current operation. 5

20. In a circuit as disclosed for amplifying and rectifying currents the combination comprising an audion having a grid, a plate and a cathode, an input circuit including said grid and cathode, an output circuit including said plate and cathode, a heater for said cathode, connections to said heater for energizing it with direct or alternating current, means to provide full wave rectification for alternating current operation and continuous conductivity for direct current 10 operation including connections between the heater and cathode of said audion, and connections from said means to the input and output circuits to provide operating potentials for said audion. 15

MICHEL MACKSOUAD.
